UNITED STATES PATENT OFFICE.

MORRIS J. HOFFMAN, OF CHICAGO, ILLINOIS.

PRINTING DEVICE.

Application filed November 20, 1922. Serial No. 601,974.

To all whom it may concern:

Be it known that I, MORRIS J. HOFFMAN, a citizen of the United States, and a resident of Chicago, Cook County, and State 5 of Illinois, have invented certain new and useful Improvements in Printing Devices, of which the following is declared to be a full, clear, and exact description.

This invention relates to printing devices 10 and its principal object is to provide interchangeable, removable and replaceable type carriers with groups of type wheels mounted thereon and bearing suitable type characters which may be set and reset to print 15 any combinations of the type characters appearing on the type wheels. The invention has been designed particularly for use in printing amounts or prices upon coupon tickets, that is to say, sheets perforated or 20 scored to form detachable coupons, each group of type wheels being arranged to print upon a coupon, whereby blank spaces on coupons may be quickly printed with the desired information. Another object is to 25 provide a type carrier, containing type wheels bearing suitable type characters and in the form of a unitary structure, which may be stored away or conveniently placed 30 in a suitable printing device when used for printing coupon tickets or other sheets. The invention consists in the several novel features hereinafter fully set forth and claimed.

The invention is clearly illustrated in the 35 accompanying drawings, in which:

Fig. 1 is a plan, partly broken away, of a printing device embodying a simple form of the present invention; Fig. 2 is an end view thereof; Fig. 3 is a vertical cross section 40 taken on line 3—3 of Fig. 1; Fig. 4 is an enlarged side elevation of a type carrier and type wheels, partly broken away; Fig. 5 is a plan of the part seen in Fig. 4; Fig. 6 is a side elevation of one of the type 45 wheels; Fig. 7 is an edge view thereof; Fig. 8 is a side elevation looking at the opposite side of the type wheel from that seen in Fig. 6; Fig. 9 is an end elevation of the type carrier and type wheels seen in Figs. 4 and 5; Fig. 10 is a detail, vertical, cross section taken on the line 10—10 of Fig. 5; Fig. 11 is a plan of the printing face of a type wheel laid out flat, and Fig. 12 is a fragmental plan of a modified form of 55 the invention.

Referring to said drawings, and first to

the Figs. 1, 2 and 3, the reference character 12 designates a type carrier holding base, preferably of elongated rectangular form, which is arranged to receive and hold the 60 type carriers in printing position. Said base may be provided with one or more seat portions 13 in its upper side that run lengthwise of the base and receive the type carriers 14. The type carriers may be held 65 on said seats against accidental displacement by latches 15 carried by the base 12 and arranged to be swung over the tops of the type carriers into engagement with studs 16. The type carriers support groups of 70 type wheels 17 which contain type characters 18 on their peripheral edges. Above the type wheels is an ink ribbon 19 which may be carried by suitable rollers 20 mounted on the base 12 and above the ink ribbon 75 is an impression making device 21 carried by a frame 22, fulcrumed on arms 23 of the base 12, which impression making device is brought down upon a coupon ticket or other sheet that is laid upon the ink ribbon 80 and the impression from the type characters, which are in writing position, is thereby made upon the coupon ticket or other sheet. The exact construction of the type carrier holding base and impression making device 85 is immaterial, so far as this invention is concerned, but has been shown for the purposes of illustration.

Referring now to Figs. 4 to 11, inclusive, each type carrier will be seen to comprise 90 two parallel spaced bars 24, which are held in spaced relation to each other by screws or rivets 25 and spacing members 26 that surround the screws or rivets 25. The spacing means shown, are not material, as other 95 equivalent connecting and spacing means may be substituted therefor. At the upper edge portions of the bars 24 are equidistant sockets, which may be formed by notching the bars as at 27, and in said notches are 100 secured the supports 28 for the type wheels. Said supports are here shown in the form of pins or rods having flattened end portions 29 that enter and seat in the notches 27 of the bars 24. The shoulders formed between the 105 flattened portions and round portions of the pins engage the inner face of the bars 24 and prevent endwise movement of the pins. In order to economize space so that the groups of type wheels may print upon narrow coupons, the groups of type wheels are staggered, as seen in Fig. 2, so that one row of 110

grouped type wheels print to one side of the other row.

The type wheels of each group are rotatively mounted upon an associated pin 28, 5 and are confined between the bars 24. When the groups are arranged in staggered fashion, as seen in Fig. 5, sleeves 30 are interposed between the groups of type wheels and one bar 24, as is clearly illustrated in Fig. 10. 10 10 While the type wheels are rotatively mounted upon the pins 28, they are normally held against rotation thereon, by friction, for instance a pad 35 of cushioned or resilient material may be supported by the carrier in 15 position to be engaged by the lower sides of the type wheels. The friction between the type wheels and the pad should be sufficient to hold the wheels in any position at which they are set although the friction should not be great enough to prevent any other wheels 20 from being turned when desired. In addition to the pad, or as a substitute therefor, coacting holding means may be provided between the several wheels of each group, as 25 for instance by lugs or protuberances 31 on one of the bars 24 which enter sockets or depressions 32 in the type wheels that are adjacent the bar. All of the type wheels may have corresponding lugs or protuberances 33 that enter corresponding depressions or sockets 32 in the adjacent type 30 wheels. The lugs and depressions form simple means for securing the type wheels against accidental rotation on their supporting pins, thereby holding certain of the type 35 characters in printing position. The printing position of the type characters may be easily changed by turning the type wheels with a pointed instrument to bring the desired type characters into position.

In the form of the invention illustrated, in Fig. 12, the axes of the type wheels are placed lengthwise of the carrier bars 24^a, instead of being placed cross ways thereof as 45 in the form illustrated in Figs. 1 to 11, inclusive. In the form shown in Fig. 12, cross bars 25^a are provided between the bars 24^a, which cross bars are provided with sockets 27^a in which the flattened ends of the pins 28^a are placed. The type wheels 17^a are rotatively mounted upon the pins, as in the preferred form.

In the forms of the invention illustrated, the type wheels contain the characters 0 to 9 55 inclusive and the fractions $\frac{1}{4}$, $\frac{1}{2}$ and $\frac{3}{4}$. In addition thereto, one type wheel of each group contains the letter "V" one the letter "O," one the letter "I," one the letter "D" so that any group may be set to print the word "void" or any number from 0 to one 60 of five figures and containing the fractions $\frac{1}{4}$, $\frac{1}{2}$ and $\frac{3}{4}$. In this way the type wheels may be set to designate values, amounts, prices and the like.

65 The device is particularly useful in print-

ing coupon tickets or other sheets where it is necessary to frequently change the amounts represented by the type characters. The changes may be made very easily and quickly and if desired, any or all of the 70 groups of type wheels may be removed from the type carriers and other type wheels bearing this kind of characters may be substituted for their places.

More or less variation of the exact details 75 of construction is possible without departing from the spirit of this invention; I desire, therefore, not to limit myself to the exact form of the construction shown and described, but intend, in the following claims, 80 to point out all of the invention disclosed herein.

I claim as new, and desire to secure by Letters Patent:

1. In a printing device, a base, spaced, 85 parallel, and connected type carrier bars removably supported therein and spaced groups of type wheels removably secured on said bars.

2. In a printing device, a base, parallel, 90 and connected type carrier bars, removably supported therein and having oppositely disposed sockets at their upper edges, type wheel supports seated in said sockets and type wheels, arranged in groups, and rotatively mounted on said type wheel supports. 95

3. In a printing device, a base, a pair of spaced, parallel, and connected type carrier bars, removably supported therein and having oppositely disposed notches formed in 100 their upper edges, type wheel supports removable seated in said notches, and type wheels arranged in groups, rotatively mounted on said type wheel supports.

4. In a printing device, a base, a pair of 105 spaced, parallel, and connected type carrier bars, removably supported therein and having oppositely disposed notches formed in their upper edges, type wheel supporting pins having reduced end portions, removably seated in said notches, and type wheels arranged in groups, rotatively mounted on 110 said type wheel supporting pins.

5. In a printing device, a base, a pair of spaced, parallel, and connected type carrier 115 bars, removably supported therein and having oppositely disposed notches formed in their upper edges, type wheel supporting pins having flattened end portions, removably seated in said notches, and type wheels arranged in groups, rotatively mounted on 120 said type wheel supporting pins.

6. In a printing device, a base, spaced, parallel, and connected type carrier bars, 125 removably supported therein, spaced groups of type wheels removably secured on said bars and means for releasably securing the type wheels of each group against rotation.

7. In a printing device, a base, spaced, 130 parallel, and connected type carrier bars,

removably supported therein, spaced groups of type wheels removably secured on said bars and co-acting means between the adjacent type wheels of each group for releasably securing said type wheels against rotation relative to each other.

8. In a printing device, a base, parallel, and connected type carrier bars, removably supported therein and having oppositely disposed sockets at their upper edges, type wheel supports seated in said sockets, type wheels, arranged in groups, and rotatively mounted on said type wheel supports and means for releasably securing the type wheels of each group against rotation.

9. In a printing device, a base, parallel, and connected type carrier bars, removably

supported therein and having oppositely disposed sockets at their upper edges, type wheel supports seated in said sockets, type wheels, arranged in groups, and rotatively mounted on said type wheel supports and co-acting means between the adjacent type wheels of each group for releasably securing said type wheels against rotation relative to each other.

10. In a printing device, a base, a pair of spaced, parallel, and connected type carrier bars, removably supported therein, groups of type wheels, removably secured on said bars in staggered relation to each other, substantially as and for the purpose set forth.

MORRIS J. HOFFMAN.
